Patented May 23, 1916.

UNITED STATES PATENT OFFICE.

WILLIAM MURPHY AND JOSEPH MILLER, OF SCHENECTADY, NEW YORK.

RAIL-JOINT.

1,184,560.

Specification of Letters Patent. Patented May 23, 1916.

Application filed October 2, 1914. Serial No. 864,677.

To all whom it may concern:

Be it known that we, WILLIAM MURPHY and JOSEPH MILLER, citizens of the United States, residing at Schenectady, in the county of Schenectady and State of New York, have invented new and useful Improvements in Rail-Joints, of which the following is a specification.

The present invention relates to improvements in rail joints, and the object of the invention is to simplify and improve the existing art by constructing a joint of two railway rails which shall be cheap, simple and thoroughly effective.

With the above and other objects in view, the improvement resides in the construction, combination and arrangement of parts set forth in the following specification and falling within the scope of the appended claim.

In the drawing: Figure 1 is a perspective view of two rails connected in accordance with the present invention, Fig. 2 is a horizontal sectional view approximately on the line 2—2 of Fig. 1, Fig. 3 is a detail perspective view of one of the chair members looking toward the inner face thereof, Fig. 4 is a detail perspective view of the end of a rail which may be employed.

Referring now to the drawing in detail, R—R designates two rails of the ordinary construction, the same having their webs, adjacent their ends, provided with the usual bolt receiving openings 2.

The chair for connecting the rail ends comprises two similar sections each designated by the numeral 3. Each of the chairs comprises a base 4 having its longitudinal edges notched for the reception of securing spikes, and the said longitudinal edges are formed with inwardly extending angular flanges 6 which rest under the base flanges of the rails. Longitudinally extending plates 7 are formed integral with the angular plates. The inner faces of the vertical longitudinally extending plates 7 are provided with vertically extending spaced grooves 8 providing vertically straight ribs 8' which abut with the sides of the webs of the rails, and grip the said rails with respect

to the joint. The plate 7 has bolt openings 50 which pass through the reduced portions thereof provided by certain of the grooves 8, and which register with the elongated bolt openings in the webs of the rails. Bolts 9 pass through the openings in the webs of the 55 rails, while locking nuts 10 engage with the threaded ends of the bolt. If desired, and as illustrated in Fig. 4 of the drawings, the webs of the rails may be likewise formed with vertically extending grooves 11. The 60 ribs between the grooves 11 may engage with the vertical plates of ordinary angle bars, and the edges provided between the ribs of the grooves will have a tendency to prevent the longitudinal movement of the said angle 65 bars, as do the said corners or edges provided between the grooves 8 and the ribs 8' of the angle bars previously referred to.

It is to be understood that while the chair plates bear sufficiently against the rails to 70 prevent the creeping thereof, the said engagement is not sufficient to interfere with the contraction and expansion of the rails.

From the above description, taken in connection with the accompanying drawing, the 75 simplicity of the device as well as the advantages thereof will, it is thought, be perfectly apparent to those skilled in the art to which such invention appertains without further detailed description.

Having thus described the invention, what we claim is:

The combination with two alining rails, of angle members arranged upon the opposite sides of the rails, said angle members 85 having their vertical plates provided with vertically extending spaced grooves forming intervening ribs, and securing elements passing through the grooved portions of the plates through the bolt openings in the rails 90 for securing the plates upon the rails.

In testimony whereof we affix our signatures in presence of two witnesses.

WILLIAM MURPHY.
JOSEPH MILLER.

Witnesses:

JAS. P. HEEKIN,
Wm. SEMPLE.
